Specification for Design.

Patented Feb. 8, 1916.

Application filed November 22, 1915. Serial No. 62,931. Term of patent 7 years.

To all whom it may concern:

Be it known that we, JOHN P. EUSTIS and ALBERT T. BROWN, both citizens of the United States of America, residing, respectively, at Newton and Arlington, county of Middlesex, and State of Massachusetts, have invented a new, original, and ornamental Design for Dish-Stands, of which the following is a specification, reference being had to the accompanying drawing, forming a part thereof.

Copies of this patent may be obtained for five cents each, by addressing the "Commissioner of Patents, Washington, D. C."

We claim:
The ornamental design for a dish stand, as shown.

JOHN P. EUSTIS.
ALBERT T. BROWN.
